SET MARK ELIMINATOR

Charles R. Beall and Luther B. Reynolds, La Grange, Ga., assignors to West Point Manufacturing Company, West Point, Ga., a corporation of Alabama

Application March 4, 1949, Serial No. 79,644

1 Claim. (Cl. 139—111)

1

This invention relates to looms, and more particularly to let-off mechanisms for looms. This invention further relates to a method of weaving.

During the weaving of textiles, the warp is commonly subjected to tension between the warp beam and the cloth take-up roller. In the case of many yarns, such as those spun of short fibers of wool or cotton, and extruded filaments, such as those of cellulose acetate, the warp tension causes the warp to "set" or stretch during overnight and other periods of shutdown. When a loom is started after a period of shutdown, the first several filling threads, due to the set of the warp and the resulting slackening of tension, are not spaced similarly to the last filling threads inserted preceding shutdown. The resulting unevenness in filling thread spacing is known as a set mark, and is the cause of rejection of considerable quantities of cloth.

It is an object, therefore, of the present invention to provide a method of operating looms to prevent the formation of set marks. More specifically, it is an object of this invention to prevent the formation of set marks by delaying let-off of the warp when a loom is started, until the action of the cloth take-up roller has compensated for any set of the warp resulting from shutdown.

It is a further object of this invention to provide means, readily adaptable to conventional looms, to eliminate the formation of set marks. More specifically, it is an object to provide means on a loom for rendering the let-off mechanism of the loom inoperative for any desired length of time.

It is a further object to provide mechanical means for temporarily rendering inoperative the let-off mechanism of a loom while the loom is running.

It is a further object to provide electrically operated means to render inoperative the let-off mechanism of a loom.

A still further object of the invention is the provision of means to render inoperative the let-off mechanism of a loom for predetermined periods of time.

Other objects of the invention will be in part obvious and in part pointed out hereinafter.

The invention and the novel features thereof will best be made clear from the following description and the accompanying drawings, in which:

Figure 1 is a side view of a conventional loom, provided with a preferred embodiment of the present invention;

2

Figure 2 is a sectional plan view taken along the line 2—2 of Figure 1;

5 Figure 3 is an enlarged detail view with parts broken away, showing the let-off mechanism of the loom of Figure 1 and the drive therefor;

Figure 4 is a perspective view of the drive slot member of the let-off mechanism of Figure 3;

10 Figure 5 is a section taken on the line 5—5 in Figure 3;

Figure 6 is a sectional view taken on the line 6—6 in Figure 3;

Figure 7 is a section taken along the line 7—7 in Figure 6;

15 Figure 8 is a sectional view taken along the line 8—8 in Figure 3, further showing details of the let-off mechanism drive;

20 Figure 9 is a side view of a loom provided with another embodiment of the present invention, employing electrically operated means to deactivate the let-off mechanism;

Figure 10 is an enlarged detail view of the let-off mechanism of the loom of Figure 9, and

25 Figure 11 is a diagrammatic view of still another modification of the present invention, employing time-controlled electrically operated means to deactivate the let-off mechanism.

30 Referring to the drawings, Figure 1 shows a preferred embodiment of the invention incorporated into a conventional loom, such as a Draper X Model loom. The loom comprises the usual parts, including the frame 11, lay 12, lay sword 13, and shipper lever 14. Suitably journaled upon frame 11 is the warp beam 15, driven through the gear 16 (as best shown in Figure 8)

35 by a let-off mechanism designated generally as 17. The let-off mechanism 17 comprises the bearing 18 mounted in frame 11 and the shaft 19 suitably journaled therein. At the inner end of shaft 19 is fixed the gear 20, in driving relationship with gear 16, and suitably spaced therefrom on shaft 19 is mounted the ratchet wheel 21.

40 The pawl carrier 22 is rotatably mounted upon shaft 19 adjacent ratchet wheel 21. Fixed to the outer end of pawl carrier 22 and offset therefrom is the pawl 23, in driving relationship with ratchet wheel 21. From the hub end of pawl carrier 22 extends the crank 24. The bracket 25, depending from frame 11, supports the housing 26, wherein the shaft 27 is rotatably supported, and the cranks 28 and 29 affixed thereto. Crank 24 is connected in driving relationship to crank 28 by link 30.

45 The rocker arm 31 is fixed to the lay rock shaft 32, and provided at its outer end with the pin 33. Pin 33 engages the drive slot member 34 by

means of the drive slot 35, which comprises the offset enlarged section 36. Drive slot member 34 is fixed to the link 37, by which it is connected to crank 29 in driving relationship. Also suitably journaled upon frame 1 is the traverse shaft 38, to which is fixed the treadle 39 and the crank 40. The outer end of crank 40 is provided with the pad 41, positioned and adapted to engage the under side of drive slot member 34.

A modification of the invention is illustrated in Figure 9, wherein is shown the warp beam 15, rotated through gear 16 by the let-off mechanism 17, comprising the ratchet wheel 21 and pawl 23. The pawl 23 is linked to plunger 42 of the solenoid 43 by the rod 44, which may be slotted at its lower end to prevent interference with the normal functioning of the pawl 23, as may best be seen in Figure 10. The solenoid 43 may conveniently be mounted upon frame 11, as shown. The wires 45 connect solenoid 43 to a source of power (not shown) and to the button switch 46, for convenience incorporated into shipper lever 14.

A still further modification of the invention is shown diagrammatically in Figure 11, wherein in circuit with solenoid 43 and button switch 46 are a plurality of the retarded break relays 47, and the selector switch 48, operable to place a selected one of the retarded break relays in circuit with the solenoid.

During ordinary operation of a loom, the warp is tensioned between the cloth take-up roller (not shown) and warp beam 15. The warp beam 15 is restrained from rotating freely to relieve such tension, as by a friction brake or similar device. The warp beam 15 is positively rotated against the influence of such restraint to feed the warp at a rate coordinated with the cloth take-up to maintain the desired warp tension. In the loom shown, the warp beam 15 is rotated by the reciprocating action of pawl 23 on ratchet wheel 21. Pawl carrier 22 and pawl 23 are reciprocated by crank 24, driven by rocker arm 31 through pin 33, drive slot member 34, link 37, bell cranks 28 and 29, and link 30. The pin 33 normally engages member 34 by means of the drive slot 35, which is designed to convey only so much of the reciprocating movement of rocker arm 31 as is desired to operate the pawl 23.

When the loom is started after a considerable period of shutdown, the warp has set and the tension therein slackened. In order to compensate for the set and return to the desired tension as soon as possible, it has been found effective to maintain the warp beam stationary through the weaving of the first several picks, whereby the action of the cloth takeup roller brings the warp tension up to the desired value. It has further been found that the adoption of this expedient eliminates the formation of set marks in the fabric, and the spacing between the filler threads inserted both before and after shutdown is uniform.

This end is attained in the preferred embodiment of this invention by means of the offset enlarged section 36 of drive slot 35. Pad 41 is so positioned that depression of the treadle 27 raises drive slot member 34 from its normal position, so that pin 33 no longer engages drive slot 35, but reciprocates within the confines of the offset enlarged section 36 of drive slot 35, as may be seen in dotted lines in Figure 1. The enlarged section 36 is designed to be adequate in size to permit the full throw of pin 33 without resultant movement of link 37.

It will be readily seen that upon resumption of weaving after a period of shutdown, the operator of the loom may, through operation of treadle 39, disengage the let-off mechanism 17, and maintain such disengagement until the desired warp tension has been reattained and the possibility of a set mark in the fabric obviated. The treadle 39 may then be released, and drive slot member 34 allowed to fall back to its normal position, whereby the let-off mechanism 17 is again activated and normal operation of the loom resumed.

In the operation of the modification shown in Figures 9 and 10, the action of pawl 23 on ratchet wheel 21 may be prevented by the rod 44, adapted and disposed to lift and hold pawl 23 out of engagement with ratchet wheel 21 as the pawl 23 reciprocates. The movement of rod 44 is effected by retraction of the plunger 42, occasioned by energization of the solenoid 43.

Upon restarting the loom by means of shipper lever 14, the operator may depress button switch 46, thereby energizing solenoid 43, and by the resulting disengagement of pawl 23 delay functioning of the let-off mechanism 17 until button switch 46 is released, whereupon the solenoid 43 is deenergized and the pawl 23 permitted to fall under the influence of gravity into normal engagement with the ratchet wheel 21.

The necessary time interval for deactivation of the let-off mechanism 17 to prevent the formation of a set mark varies with the period of shutdown, the type of yarn or filament being woven, and other variables. This interval may vary from that necessary to weave two or three picks to the time required to weave twelve or more picks. It has been found that a moderately experienced operator may accurately judge and effectuate the necessary time delay in activating the let-off mechanism by means of the modifications of the invention above described. The period of delay between the starting of the loom and the starting of the let-off mechanism may be accurately and automatically predetermined, however, by means of the further modification diagrammatically illustrated in Figure 11. In this modification, the push button of button switch 46 is depressed simultaneously with the starting of the loom, whereupon a circuit is set up through the then closed contacts of the retarded break relay 47 and also through the pawl actuating solenoid 43. Energization of the latter immediately effects disengagement of the pawl 23 from the ratchet wheel 21. A shunt circuit is also set up through the retarded coil of the retarded break relay 47, and when the coil is completely energized its contacts will open and deenergize the pawl actuating solenoid 43, whereupon the pawl falls under the influence of gravity into engagement with the ratchet wheel 21. By providing a plurality of retarded break relays 47, each operable to open its contacts after a different time interval, and selecting the desired retarded break relay by means of the selector switch 48, the period of time during which the pawl is held out of engagement may be accurately determined and preselected by the operator before starting the loom. Obviously, any equivalent time delay circuit opening devices may be employed instead of the retarded break relays mentioned above.

In the event of a shutdown of such short duration as not to cause the warp to set, it will be apparent that the loom may be started without the use of the mechanism of this invention, so that functioning of the let-off mechanism begins simultaneously with the functioning of the loom.

It will thus be seen that there has been provided by this invention a method and apparatus in which the various objects hereinbefore set forth together with many practical advantages are successfully achieved. As various possible embodiments may be made of the mechanical features of the above invention and as the method herein described may be varied in the various parts, all without departing from the scope of the invention, it is to be understood that all matter hereinbefore set forth or shown in the accompanying drawings is to be interpreted as illustrative and not in a limiting sense.

What is claimed is:

In combination with a loom, a warp beam, a ratchet wheel and actuating pawl for rotating said warp beam to let off the warp, a reciprocating pawl carrier driving said actuating pawl, a rocker arm fixed to the lay rock shaft of said loom, a pin extending from the outer end of said rocker arm, a mechanical linkage between said

pin and said pawl carrier to actuate said pawl carrier by means of said pin, said linkage comprising a drive slot enclosing said pin, and mechanical means for temporarily disengaging said pin from said drive slot while said loom is operating.

CHARLES R. BEALL.
